Primary Examiner — Cathron C Brooks*Assistant Examiner* — W. A. Teddy Falloway(74) *Attorney, Agent, or Firm* — McKee, Voorhees &
Sease, PLC(57) **CLAIM**I claim the ornamental design for a chemistry delivery
device, as shown and described.

DESCRIPTION

FIG. 1 is a perspective view of a chemistry delivery device
according to an embodiment of the invention;FIG. 2 is an exploded perspective view of the chemistry
delivery device of FIG. 1, including a puck-shaped
chemistry;

FIG. 3 is a side view of FIG. 1;

FIG. 4 is an exploded side view of the chemistry delivery
device of FIG. 1, including a side view of a puck-shaped
chemistry;FIG. 5 is an exploded perspective view of the chemistry
delivery device of FIG. 1, including a puck-shaped chemistry
portion placed in the interior of the device;FIG. 6 is a top view of an alternative embodiment of the
chemistry delivery device of FIG. 1; and,FIG. 7 is a view of an alternative embodiment of the
chemistry delivery device of FIG. 1.**1 Claim, 4 Drawing Sheets**| (56)	References Cited
